CLAIM

The ornamental design for a laptop stand with adjustable tilt, as shown and described.

DESCRIPTION

FIG. 1 is a top plan view of a laptop stand with adjustable tilt showing my new design;

FIG. 2 is a front elevational view thereof;

FIG. 3 is a right side elevational view thereof;

FIG. 4 is a front perspective view thereof;

FIG. 5 is a back perspective view thereof;

FIG. 6 is a front perspective view thereof as shown in FIG. 4, in a second position; and,

FIG. 7 is a back perspective view thereof as shown in FIG. 5, in a second position.
